UNITED STATES PATENT OFFICE

162,205

CHILD'S CABINET

Fosca Marsyl, New York, N. Y.

Application May 9, 1950, Serial No. 9,841

Term of patent 14 years

(Cl. D33—19)

To all whom it may concern:

Be it known that I, Fosca Marsyl, a citizen of the United States of America, residing in New York city, county of New York, and State of New York, have invented a new, original, and ornamental Design for a Child's Cabinet, of which the following is a specification, reference being had to the accompanying drawing, forming part thereof, wherein:

The characteristic features of my design reside in the portions shown in full lines in the drawing.

I claim:

The ornamental design for a child's cabinet, substantially as shown and described.

FOSCA MARSYL.
